UNITED STATES PATENT OFFICE

JAMES E. BANCROFT, OF DETROIT, MICHIGAN, ASSIGNOR TO DOOR-MOTIVE CORPORATION, OF WORCESTER, MASSACHUSETTS, A CORPORATION OF MASSACHUSETTS

DOOR-OPERATING MECHANISM

Application filed May 2, 1928. Serial No. 274,511.

This invention relates to door operating mechanism and more particularly to power actuated apparatus arranged to open and close large doors.

5 It has heretofore been proposed to utilize an electric motor for the operation of doors, but these previous constructions have usually employed various complicated and expensive types of reducing gears in order to transform the comparatively rapid speed of the motor down to a relatively slow speed suitable for the movement of the doors.

It is accordingly one object of my invention to provide a door operating mechanism 15 actuated by an electric motor which will operate the doors at a desired speed without the necessity of utilizing complicated speed reduction devices and which will be inexpensive to manufacture and simple to erect and install.

Various problems arise in designing a door operating mechanism which is adaptable to various forms of existing installation of doors. It frequently happens that the ceiling is low and the space between the top of 25 the door and the ceiling is therefore small, making it difficult to install the mechanism in such a small space. It also frequently happens that there is a wall perpendicular to the normal closed position of the door which is near the door at one or both sides thereof and therefore limits the space within which the door operating mechanism may be installed.

30 It is accordingly a further object of my invention to provide a door operating mechanism which will require a minimum of space and can be easily installed in connection with existing door installations where the door extends nearly to the ceiling or where there is some other obstruction limiting the available space, and particularly one which is well adapted for use in connection with doors of the swinging or folding type.

45 With these and other objects in view as will be apparent to those skilled in the art, my invention resides in the combination of parts set forth in the specification and covered by the claims appended hereto.

50 In accordance with my invention and to

the accomplishment of these objects, I propose to utilize a nut and a screw threaded therethrough which are operatively driven by a suitable motor and which are connected to the door by mechanism that will serve in cramped quarters to actuate it easily and positively. One of these screw threaded parts is connected to the motor, which is preferably an electric motor, and arranged to be rotated thereby. The other part is 55 connected to the door and preferably arranged to move in substantially a straight line as the door is opened or closed. I preferably rotate the screw and this may be done by connecting it directly to the motor by 60 means of a suitable flexible coupling so that the screw is rotated at motor speed and is free to swing slightly and thus avoid the transmission of any bending action to the motor shaft. When the doors to be operated 65 are of the swinging or folding type, the nut is connected to the door through a suitable linkage so as to cause it to move in substantially a straight line as the door swings about its hinges. 70

75 Referring to the drawings illustrating one embodiment of my invention and in which like reference numerals indicate like parts:

Fig. 1 is a plan view of my apparatus applied to a set of folding doors, the doors being shown in the closed position and certain parts being removed and others broken away for clearness of illustration:

Fig. 2 is a plan view of the installation shown in Fig. 1, with the doors shown in 85 the open position;

Fig. 3 is a front elevation of the installation shown in Fig. 1, with the doors shown in the closed position;

Fig. 4 is a side elevation of a portion of 90 the apparatus, showing the method of connecting the arm and link to the door and lintel; and

Fig. 5 is a side elevation showing one method of mounting the motor and limit 95 switch.

The embodiment of my invention illustrated in the drawings comprises a door operating mechanism installed to operate a set of doors of the folding type. As shown, 100

a wall 10 may be provided with a rectangular opening therethrough and arranged to form a casing for the doors. A pair of doors 11 and 12 are hinged to the door casing at 14 and 15 respectively, so that they may swing about vertical axes on opposite sides of the casing. A second pair of doors 17 and 18 are hinged to the first doors at 20 and 21 respectively, so that they may fold against the doors 11 and 12 when they are in the open position, as shown in Fig. 2. Various arrangements may be employed to guide the free edges of the doors 17 and 18 as they move from open to closed position and vice versa.

15 One simple means well known in the art comprises a pair of arms 23 and 24 which are pivoted to the doors 17 and 18 at the points 26 and 27 respectively. These arms are long and their opposite ends (not shown) are fulcrumed to a suitable stationary support such as the ceiling or a beam. In this manner the free edges of the doors 17 and 18 are guided in an arc of a circle having a comparatively long radius.

20 25 In order to open and close the doors by power I provide a suitable motor, preferably an electric motor 29. This motor may be mounted slightly above the top of the doors, and if the ceiling is low it may be attached directly thereto. In the drawings I have shown the motor attached to a bracket 30 which is mounted on the wall 10 above the doors. In Fig. 1 this bracket has been removed, in order to show the construction underneath.

Since electric motors ordinarily used for door operation rotate at a comparatively high speed, it is necessary to use some form of speed reducing mechanism to connect the motor to the doors in order that they may open and close at the desired speed. I have found a screw and nut to be particularly desirable for this purpose and accordingly when the doors are of the double type shown 40 in the drawings, I provide a pair of screws 32 and 33 which are threaded through nuts 35 and 36. Either of these parts may be rotated and the other parts connected to the doors to move the same. In the preferred 45 embodiment of the invention illustrated I have shown the screws 32 and 33 as being rotated by the motor 29 and the nuts 35 and 36 are connected to the doors by a suitable means so that the doors open and close as the nuts move back and forth along the screws. These screws are of opposite hand, as shown, screw 32 having a left hand thread and screw 33 a right hand thread.

The nuts are connected to the doors in such 50 a manner that they move in substantially a straight path in line with the axis of the motor as the doors are opened or closed. For this purpose I provide a pair of arms 38 and 39 which are pivoted to the doors 11 and 12 at the points 41 and 42 respectively. These

pivotal points 41 and 42 are spaced a considerable distance from the hinges 14 and 15. The arms 38 and 39 are provided on their undersides with braces 44 and 45 respectively in order to strengthen them and permit them to support the weight of the parts resting thereon without sagging. Links 47 and 48 are provided, each having one end pivoted to the casing at points 50 and 51 respectively between the arm and the corresponding door hinges. Each link 47 and 48 is pivotally joined at its outer end to the adjacent arm at points 53 and 54 respectively. The links are made of such sizes and relative proportions that they will fold into a comparatively small space when the doors are open as shown in Fig. 2 and thus avoid any interference with the adjacent wall 55 shown in the drawings.

The nuts 35 and 36 are mounted upon the arms 38 and 39 at points which are so selected that the nuts move in substantially a straight line parallel to the door casing during the operation of the doors. Each nut is free to rotate relative to its corresponding arm about a vertical axis, as shown in Fig. 4. For this purpose the nuts 35 and 36 are mounted in yokes 57 and 58 which are provided with downwardly extending spindles 60 and 61 respectively. These spindles are free to rotate in suitable bosses 63 and 64 in the arms and braces. Each nut is preferably pivotally mounted about a horizontal axis in its corresponding yoke as illustrated. This construction forms a universal mounting for the nuts so that they are free to align themselves with the screws, thereby preventing any binding between the nuts and screws which might be caused by slight errors in alignment or sagging of the doors.

Since the construction described does not give a perfect straightline motion to the nut it is necessary to permit the screws to swing slightly during operation of the doors. I therefore provide universal couplings 66 and 67 between the motor and the screws 32 and 33 respectively, it being understood that the motor is provided with a shaft extension at each end thereof for this purpose.

It is desirable to stop movement of the doors automatically as they reach either one of their extreme positions and for this purpose I may mount a sprocket 70 on the motor shaft and connect it by means of a chain 71 to a second sprocket 72 which operates an enclosed limit switch 74. This limit switch, which may be conveniently mounted beneath the motor supporting bracket 30, may be of any suitable construction well-known to those skilled in the art. Since various methods of operating door mechanism of this general type are well-known to those skilled in the art, such as push buttons, floor trips, etc., I have not illustrated any particular arrangement for the electri-

cal circuits since they form no part of the present invention.

The operation of my invention will now be apparent from the above disclosure. The 5 motor having been started by means of any suitable switch the screws 32 and 33 are thereby rotated and the nuts 35 and 36 travel along the screws and thus cause the doors to open or close. As the doors approach either of their extreme positions the limit switch operates to break the motor circuit and bring the doors to a stop. Since the motor is the highest part of the whole mechanism, the apparatus can be used in 10 connection with existing door installations where the space is very limited. The mechanism is simple and inexpensive to manufacture and all gearing has been eliminated. In case of ordinary double swinging doors 15 which do not have the folding feature, the operation will be identical. In such a case the parts 17 and 18 will be made integral with the doors 11 and 12 and the members 23 and 24 will not be utilized.

Having thus described my invention, what I claim as new and desire to secure by Letters Patent is:—

1. A device for operating a door hinged to a casing and arranged to swing about a vertical axis, comprising an arm having one end adapted to be pivoted to the door at a point spaced from said axis, a link having one end arranged to be pivoted to the casing at a point between the arm and the axis, said arm and said link being pivotally joined at their outer ends, a nut mounted on said arm and arranged to revolve relative thereto about a vertical axis, a screw threaded through the nut, and a 30 motor connected to the screw to rotate the same, whereby operation of the motor will cause the door to open or close.

2. In combination, a door casing, a door hinged to the casing and arranged to swing about a vertical axis, an arm having one end pivoted to the door near its top and at a point spaced from said axis, a link having one end pivoted to the casing above the door and at a point between the arm and the axis, 45 said arm and said link being pivotally joined at their outer ends, a nut mounted on said arm intermediate of its length and arranged to revolve relative thereto about a vertical axis, a screw threaded through the nut, a rotatable motor, and a universal coupling connecting the motor directly to the screw, whereby operation of the motor will open or close the door.

3. In combination, a door casing, a pair 60 of doors hinged to the casing and arranged to swing about vertical axes on opposite sides of the casing, a pair of arms each having one end pivoted to one of the doors at a point spaced from the door axis, a pair of 65 links each having one end pivoted to the

casing at a point between one of the arms and the door axis, each arm and the adjacent link being pivotally joined at their outer ends, a nut mounted on each arm intermediate of its length and free to revolve relative thereto about a vertical axis, a pair of screws of opposite hand, each being threaded through one of the nuts, a rotatable motor provided with a shaft extension at each end thereof, and universal couplings connecting each screw with one end of the motor shaft, whereby operation of the motor will open or close the doors simultaneously.

4. In combination, a door casing, a pair of doors hinged to the casing and arranged to swing about vertical axes on opposite sides of the casing, a pair of arms each having one end pivoted to one of the doors near its top and adjacent to the edge opposite its hinge, a pair of links each having one end pivoted to the casing above the door at a point between one of the arms and the door axis, each arm and the adjacent link being pivotally joined at their outer ends, a nut mounted on each arm intermediate of its length and free to revolve relative thereto about a vertical axis, a pair of screws of opposite hand, each being threaded through one of the nuts, an electric motor provided with a shaft extension at each end thereof, universal couplings connecting each screw with one end of the motor shaft, a second pair of doors each of which is hinged to one of the first mentioned doors, and means to guide the free edges of the second doors as the first doors are opened and closed by the operation of the motor.

Signed at Detroit, Michigan, this 27th day of April, 1928.

JAMES E. BANCROFT.
